UNITED STATES PATENT OFFICE.

WILLIAM A. WATSON, OF MALDEN, MASSACHUSETTS, ASSIGNOR TO NATIONAL PIANO COMPANY, OF BOSTON, MASSACHUSETTS, A CORPORATION OF MAINE.

PNEUMATIC-VALVE MECHANISM.

1,101,979.

Specification of Letters Patent.

Patented June 30, 1914.

Application filed December 16, 1912. Serial No. 737,074.

To all whom it may concern:

Be it known that I, WILLIAM A. WATSON, a citizen of the United States, and resident of Malden, in the county of Middlesex and 5 State of Massachusetts, have invented certain new and useful Improvements in Pneumatic-Valve Mechanism, of which the following is a specification.

This invention relates to valve structures 10 for pneumatically controlled mechanisms, and is especially intended for use in connection with self-playing musical instruments, although the present invention is not limited thereto, as it may be employed in connection 15 with mechanisms other than musical ones which employ devices actuated by "pneumatics."

In mechanisms of this character as heretofore generally constructed, it has been difficult 20 to inspect and repair the automatic valve mechanisms because of the necessity of removing other parts in order to gain access to the valves and other contained members. In my applications 277,490, filed September 8, 1905, and 674,849, filed February 1, 1912, I have disclosed and claimed constructions of shells which carry valve devices, such shells being seamless and independently removable from the piano or 25 other instrument without disturbing other parts, the shells carrying the valves which control the passages for the individual operation of power pneumatics.

The object of the present invention is to 30 provide improvements in the structure of the shell, which I shall now proceed to describe and claim.

Of the accompanying drawings: Figure 1 is a sectional elevation of my improved 35 shell unit and valve mechanism, in connection with sufficient other parts of a "self-playing" piano to illustrate the utility of the present invention; Fig. 1^a is a detail perspective of the lifter or pitman for the 40 top valve; Fig. 2 represents a longitudinal section of the metal shell, on line 2—2 of Fig. 4, omitting the members inclosed therein; Fig. 3 is an elevation of the shell from the inner end; Fig. 4 is a plan 45 view of the shell; Fig. 5 is an outer end elevation of the shell; Fig. 6 represents a horizontal section on line 6—6 of Fig. 2;

Fig. 7 represents a section on line 7—7 of Fig. 6; Fig. 8 is a plan view of the pneumatic block, removed from the shell; Figs. 55 9 and 10 represent sections on lines 9—9 and 10—10, respectively, of Fig. 8; Fig. 11 is a detail plan of the removable cover for holding the top valve in place; Fig. 12 represents a section on line 12—12 of Fig. 11; 60 Fig. 13 is a front elevation of several shells, showing the method of mounting and securing them relatively to each other. Figs. 1 and 13 are practically on a scale of full size, the other figures being on a larger scale. 65

To facilitate description, reference numerals are employed to designate tangible parts of the structure, while reference letters are employed to designate spaces, passageways or ports.

Referring first to Fig. 1, 20 indicates a portion of the frame, and 21 indicates one of the stickers which actuates a sticker of the piano action, said sticker being actuated by a lever 22 pivotally supported at 23 and 75 pivotally connected at 24 to a vertical link 25 which has an opening (indicated by dotted lines) to receive a projection or toe 26 that is carried by the lower or movable member of the power pneumatic 27. When 80 the pneumatic 27 is collapsed, due to the exhaustion of air therefrom, the member 21 is raised and, in the case of a pneumatic piano, a particular hammer of the action is operated. In said Fig. 1 is represented a 85 tube board 28 having ducts or windways *a*, each of said ducts communicating with a small tube 28', there being a row of such tubes, one for each shell and duct *a*, extending transversely of the vacuum chamber *b* 90 in casing or shell 28^a.

There is, of course, a power pneumatic for each duct *a* and tube 28', while the vacuum chamber *b* is continuous for the entire series. Removably connected with each 95 power pneumatic 27 and with the wind chest, is a valve-carrying shell 29, which shell embodies most of my present improvements, each shell and its valves being, as presently described, so located that it controls the communication between its power pneumatic and the vacuum chamber of the wind chest. 100

As the shells 29 and their contained

mechanisms are duplicates of each other, a detailed description of one will be ample. Each shell is formed with a slotted lug 30 at its front end, a screw 31 passing through the slot of such lug into the front end of the upper member of the pneumatic 27, thereby effecting a tight joint with said pneumatic. The sides of the shell 29 are formed with horizontal semi-circular grooves 32 and with flat-faced bosses 33 to receive the pressure of the heads of suitable screws or bolts 34 which extend into the front of the casing or shell 28². Each screw fits the grooves 32 of two abutting shells, and by the removal of any two of said screws or bolts, the shell 29 between said screws or bolts can be easily withdrawn from position, after loosening or removing its front screw 31. This structure enables said shells to be fitted closely to each other so as to aid in supporting each other and to occupy the least possible space. The internal surfaces of the walls corresponding to the grooves 32 present ribs which reinforce the structure.

The shell 29 is formed with internal ribs 35 which serve to still further reinforce the shell, and also serve to hold the pneumatic block in place, as hereinafter described, and with a horizontal partition 36 and a vertical partition 37. The rear end of the shell is open and is held against the front wall of the vacuum chamber by the bolts 34, suitable packing material being employed as at 43, Fig. 1. The shell is formed with a passageway *g* (Figs. 1, 2, 3 and 4) above the front portion of the partition 36 and extending down in front of partition 37, the ends of said passageway being closed as at 39, 40. For convenience of manufacture, the passageway is so made as to require a plug to be inserted as at 38.

The partition 36 is formed with an opening *i* across which extends a bridge 41 having a hole 42 to guide the disk valve spindle hereinafter described.

Removably fitted in the bottom of the main chamber of the shell and retained there by the internal ribs 35, is a block 44 which is preferably made of wood, said block having a raised section 45 which might be integral with the main body 44, but is preferably a separate piece suitably secured to said body. Secured to the top of the section 45 is a diaphragm or flexible cover 46 which may be of kid. A similar diaphragm or flexible cover 47 is secured to the upper face of the block 44 and extends down across the rear end of said block to form a packing between said rear end and the front face of trunk shell 28². A piece of kid or other suitable material to form a packing 48 is secured to the front end of the block 44. Secured to the cover 47 is a disk 49 which may be of cardboard or other suitable material cemented to said cover,

the purpose of said disk being to contact with the lower end of the valve spindle above it, as presently described. Secured to the cover 46 (see Figs. 1, 8 and 9) is a disk 50 having a top facing 51 of suitable material to enable said disk to act as a valve, as hereinafter described. A small vent 53 is formed in the section 45.

As best illustrated in Fig. 1, the block has its raised portion reaching to such a height 75 that the flexible cover and its valve member 50 are in close relationship to the lower end of the passageway 59 which extends up through the roof of the chamber in the shell. Therefore, while the block is readily removable through the open side of the shell to permit examination or repair or cleaning of the valve, yet when the block is replaced it immediately assumes position to actuate the lifter 60.

The block 44 is formed with two horizontal borings *c*, *e*, which may be termed "blind ducts," in that they do not permit the passage of air, because they terminate respectively in pockets *d*, *f* under the diaphragms 46, 47, in order that the latter may be caused to rise and fall, according to the relationship of air pressure above them, resulting from variations of pressure in the ducts *c* and *e*, as hereinafter described. It 95 is to be understood however that a very slight amount of air is permitted to escape through the vent 53 for a purpose that will be understood presently.

Mounted in the hole 42 of bridge 41, and above the disk 49, is a spindle 54 (Fig. 1), having lower and upper valve disks 56, 57. The construction of this spindle and its disks may be as described in my said application 674,849. Above the valve disk 50, 105 the shell 29 is formed with a vertical rectangular aperture 59 (Figs. 2, 4 and 6) for the valve lifter 60 (Figs. 1 and 1^a), said aperture intersecting one end of the passageway *g*. The valve 61 normally rests upon a raised seat 58 surrounding the upper end of the aperture 59, in position to be raised by the lips 62 of the lifter 60.

The seat for the upper disk valve 57 comprises a removable ring (Figs. 1 and 4) having an annular rib seat 63 and a marginal flange 64 resting on a seat 65 (Fig. 2) around an opening 66 in the top of the shell. The flange 64 is engaged by the heads of screws 67 which pass through ears 68 of said flange. By removing the screws the ring can be lifted away to enable the spindle 54 and its two disk valves to be removed through opening 66. The ring has a bridge strip 69 provided with a hole 70 to constitute a bearing for the upper end of the spindle 54.

The object of forming the ring with the annular rib seat 63 which presents a rounded surface toward the valve 57 is to prevent 130

the "whistling" noise that often results from an inrush of air when there is a thin edge at one side of a narrow passage.

The lifter 60, as best shown in Fig. 1, is angular in cross section, and it has a lip or lips 62 to bear on the top of the shell within the seat 58 so as to prevent it from dropping below its proper normal position, said position being with its lower end slightly above the valve facing 51. Said lip or lips, when the lifter is raised as hereinafter described, lifts the valve 61 from seat 58. The angular shape of the lifter provides a clear passage for air along its inner side, while the outer side fits an angle of the rectangular passage 59 so that said lifter can not turn and obstruct the passage of air through passageway *g*, thus insuring uniformity of flow. In other words, the lifter remains in one corner of the angular passageway with its inner or reentrant side facing the end of the passageway *g*, and consequently it can never present the slightest obstruction to the passage of air. Since the lifter is not connected in any way with either the upper valve 61 or the lower valve 50 which latter actuates the lifter, there being merely a permitted contact of these three parts, there is nothing to interfere with the perfect seating of either valve.

To hold the little disk valve 61 from permanent dislodgment, I provide a retainer comprising a dome-shaped cap 72 (Figs. 1, 11 and 12) having an opening 73 through which the valve 61 may be examined. The said cap is formed with an ear 74 having an opening 75 for a screw 76 by means of which said cap is secured to the top of shell 29. The top of the shell is convex, and the dome-cap is formed so that its lower edge fits the curvature of the said top snugly, but not air-tight. Therefore said cap will be held in central position by the one screw 76, but by loosening said screw, the cap can be swung aside to give access to the valve, without entirely detaching the cap. This cap 72 also acts as a muffler to prevent the issuance of any slight noise that might result from the operation of the valve 61 or lifter 60.

No part of the cap 72 forms a valve seat, it serving merely to prevent dislodgment and loss of the small loose valve 61, and therefore no part of it is air-tight. If no inspection of the valve be desired the opening 73 might be omitted as sufficient air can leak under the edges of the cap.

The three co-operating elements comprising the two valves 51, 61, and the lifter or movement transmitter 60 do not touch each other when at rest, as shown in Fig. 1, there being normally no physical contact or connection at all between them. It is only when the shell is in use, the piano or other instrument being in operation, that the said three

elements ever touch each other as presently described. Therefore the elements 60, 61 can be easily removed from the shell whenever it is necessary or desirable to do so.

The operation is as follows: It being understood that, by mechanism well known, there is a constant partial vacuum existing in the chamber *b*, or, in other words, the air in said chamber is under tension. The passage of the record sheet of the usual tracker board, from which separate tubes or conduits lead to the ducts *a* in the board 28, causes perforations of said record sheet to admit atmospheric pressure to one or another of the ducts *a*. It is to be understood that each duct *a* communicates through the board 28 and small tube 28' with one primary shell. Only one of such communications or passageways is indicated in Fig. 1. Assuming that the one duct indicated at *a* in Fig. 1 has been opened to the atmosphere by the passage of a perforation of the record sheet as mentioned, such pressure is instantly admitted to the duct *c* (Figs. 8, 9 and 10), resulting in the diaphragm 46 being lifted because the space or chamber *m* in the shell above said diaphragm is subject to the reduced pressure due to said chamber or space *m* being constantly open to the vacuum or tension chamber *b*. The rise of the diaphragm 46 raises the valve 50, 51 and causing the latter to act through the lifter 60 to lift the valve 61 from the seat 58 (Figs. 1 and 2) when the valve 50, 51 reaches its uppermost position, it closes the passageway through the aperture 59, the lifter 60 occupying but a small space in said aperture. Said lifter is of course so located as not to interrupt the passage of air to and through the passageway *g*. The pressure admitted to passageway *g* is instantly transmitted through the hole *A* in the vertical partition 37 and into the duct *e* and pocket *f* of the block 44, thus causing the cover or diaphragm 47 to rise, carrying with it the disk 49 and lifting the spindle 54 and the two valve disks 56, 57. This upward movement of the spindle 54 opens the aperture *i* in the partition 36 of the shell and causes the upper valve disk 57 to seat against the rib 63. Thus the admission of atmospheric pressure to the chamber *l* above the partition 36 is cut off and communication is established between the chambers *b* and *l* through the chamber *m* and also to the passageways *k* (Fig. 3), each side of the rib containing the passageway *g*. Since the passageways *k* communicate with a port *n* (Fig. 1) in the upper member of the power pneumatic 27, the reduced pressure in the passageways *k* and chamber *l* result in atmospheric pressure actuating the lower member of the power pneumatic so as to cause the operation of the sticker 21 through the connections hereinbefore described. 130

- After the perforation of the record sheet has passed beyond the opening of the tracker board which communicates with the selected duct *a*, the cutting off of the atmospheric pressure from duct *c* and pocket *d* permits valve 50, 51 to descend instantly under the influence of the atmospheric pressure upon the top of valve 61, the vent 53 in the section 45 permitting this to be done.
- 10 The quick downward movement of the valve 50, 51 is aided by the fact that the reduced pressure in chamber *m* is communicated through said vent to the pocket *d*. Said vent is not large enough to permit air to escape so freely through it during the first 15 described upward movement of the diaphragm 46 as to interfere with the lifting thereof. The downward movement of the said diaphragm and the lifter carried thereby is also aided by atmospheric pressure on valve 61, tending to cause the loose member 60 to push the lower valve down. As the upper valve 61 seats, it cuts off atmospheric pressure from passageway *g*, and the descent of valve 50, 51 from its seat against the under side of partition 36 opens communication between passageway *g* and chamber *m*. This results of course in permitting the diaphragm 47 above the pocket *f* 20 to descend so that the disk 49 will permit spindle 54 to return to the position shown in Fig. 1, closing the communication between chambers *l* and *m* but opening chamber *l* to atmospheric pressure, which is instantaneously communicated through passageways 25 to port *n* to the interior of the power pneumatic 27, so that the latter will, through the connection described, permit sticker 21 to descend.
- 30 As will now be understood, I have provided a structure of shell unit which may be readily removed from the vacuum chest without disturbing any of the interior adjustments and without risk of affecting its utility. When so removed, its true condition and that of its contained members may be readily disclosed whenever necessary. The structure of the shell, although seamless, is such that all of the moving or movable parts may be passed thereinto or removed therefrom, and the walls and partitions are integral so as to prevent any possibility of leakage of air.
- 35 Having described my invention, I claim:
1. A primary shell for an instrument of the character described, having an air passage, a valve therefor, a lifter for said valve located in said passage, and an actuator valve for said lifter, said valve, lifter and actuator valve being disconnected and adapted to move independently of each other.
2. A primary shell for an instrument of the character described, having an air passage, an upper valve therefor, a lifter for

- said valve located in said passage, and a lower actuator valve for said lifter, the lifter being angular in cross section and having no positive connection with said upper valve or with the actuator valve.
3. A primary shell for an instrument of the character described, having an air passage, valves for the opposite ends of said passage, and a lifter for one of said valves, said valves and lifter being separate from each other and independently movable.
4. A primary shell for an instrument of the character described, having an air passage, a lifter located in said passage and having a lip at its upper end to prevent it from dropping, a valve above said lifter, said valve having no positive connection with the lifter and an actuator for said lifter.
5. A primary shell for an instrument of the character described, having communicating air passageways one of which is angular in cross section, a valve for the upper end of the angular passageway, and a lifter angular in cross section located in said angular passageway, the re-entrant side of the angular lifter facing the end of the intersecting passageway.
6. A primary shell for an instrument of the character described, having an air passage, a valve for the upper end of said passage, and a retainer for said valve, said retainer comprising a dome-shaped shell having a single ear pivotally connected to the primary shell, the dome-shaped shell being otherwise free, to enable it to be swung aside.
7. A primary shell for an instrument of the character described, said shell having a curved top, an air passage through said top, a valve for the upper end of said passage, and a retainer for said valve, said retainer comprising a shell having an edge to fit the top of the primary shell and provided with an ear pivotally connected to said shell.
8. In an instrument of the character described, a tube board, a plurality of primary shells having air passages and valves, and a wind-way intermediate the tube board and said valves, said wind-way being in communication with all of the shells, tubes extending through the wind-way and connecting individual shells with individual ducts of the tube board.
9. The combination with a shell unit having an interior chamber and ducts or passageways communicating therewith, of a block removably mounted in said chamber, said block having a raised section and having ducts leading to the latter and to another portion of the block, flexible coverings over said ducts, and valves positioned to be actuated by the flexing of said coverings.

10. A primary shell for an instrument of
the character described, having an air pas-
sage, a valve for the upper end of said pas-
sage, and a movable dome above said valve,
said dome being free from air tight connec-
tion with the shell.

In testimony whereof I have affixed my
signature, in presence of two witnesses.
